UNITED STATES PATENT OFFICE.

LORTON A. WESTERVELT, OF READING, PENNSYLVANIA.

NECKTIE FASTENING.

Application filed September 24, 1925. Serial No. 58,431.

My invention relates to an improved made-up necktie embodying stud-engaging means adapted to cooperate with the projecting portion of a collar securing device in positioning and fastening the tie.

The main purpose of the invention is to provide a tie structure in which a suitable stud-engaging device is so embodied as, first, to utilize the main portion of the thickness of the tie body as a container for the engaging stud; and second, to insure satisfactory symmetrical positioning of the tie in close contact with the collar through which the engaging stud device is passed in securing the latter to the shirt band; further purposes being to combine in such a necktie and its engaging stud device, neatness of appearance and simplicity and satisfactoriness of cooperation, as well as economy of production.

The accompanying drawings illustrate a preferred embodiment of the invention as hereinafter specifically described, and the novel features are clearly defined in the subjoined claim.

Fig. 1 is a rear-face perspective view of a made-up bow tie having my stud-engaging spring-clip rearwardly inserted into the body material of the tie and secured thereto.

Fig. 2 is a similar view of a portion of a shirt band, and of a separate collar as commonly secured to the band by means of a collar button passed through registering button holes; Fig. 3 showing my preferred form of tie-engaging stud device as a collar-buttoning means.

Fig. 4 is a central cross-sectional view of the engaged clip and stud, indicating in dotted lines the embraced fabrics; Figs. 5 and 6 are separate perspective views thereof; and Fig. 7 indicates the application of my device to a different form of made-up necktie.

The particular bow tie indicated is made up ordinarily of two parallel folded strips of fabric forming a central body portion *a* around which a fabric band *b* is commonly secured so as to provide a compacted bunching of substantial thickness.

In my improved tie structure this body thickness of the tie is utilized by inserting therein a stud-engaging clip 10, the main portion 11 of which extends through a rearward slitting 12 of the rear portion of such bunched fabric, into inner contact with the

front layer of the material, so as to provide a stud-receiving device embodied in the tie body and permitting the engaging stud to be passed into the latter until the rear face of the tie is pressed against the collar *c* on shirt band *d*. This inserted clip device 10 is secured to the rear face of the tie body, as by sewing stitches 14^a, with its stud-entering mouth 13 about flush with said face; the device, as shown, being formed from a strip of sheet material, such as spring brass or steel, folded to elongated U-shape to form the main stud-receiving body 11, and having oppositely bent end portions 14, 14 bearing against the rear face of the tie body.

The entering mouth 13 of the clip 10 is shown as a narrow rectangular opening, widening somewhat between the rearwardly extending walls of the portion 11 so as to localize the frictional grip upon the entering collar stud.

This collar stud 15 is also preferably formed of bent up sheet material; the flat stud portion 16 thereof extending at right angles to the flat head portion 17, and being adapted to pass loosely through the usual button holes of the shirt band and collar and project sufficiently to be entered through the clip mouth 13 into the tie-inserted clip body 11. The projected end of the portion 16 is preferably widened slightly so as to provide retaining offsets 18 for preventing accidental withdrawal through the button holes before attachment of the necktie.

It will be seen that my improved necktie in itself is neat in appearance, substantial in construction, and simply and economically made; that it may be secured to or detached from the projecting collar stud by simply overcoming the slight but sufficient friction of the inserted spring clip, the engaging movement allowed by the inserted stud-receiving clip permitting the rear face of the tie to be snugly seated against the collar; and that the prevention of turning movement of the tie either upon the stud or in the collar connection insures its symmetrical positioning at all times.

A collar-stud properly adapted thereto can be conveniently and cheaply furnished with each of my inserted-clip ties to insure satisfactory cooperation as described, but the form of inserted clip may obviously be modified so as to permit of use in combina-

tion with a collar stud of correspondingly modified form, and without departing from the essential features of my invention.

What I claim is:—

- 5 A stud engaging necktie comprising a made-up fabric tie having a spring clip imbedded therein and secured thereto, said clip consisting of a strip of resilient material bent about midway between its ends
- 10 into U-shape, to provide opposite jaws form-

ing substantially straight parallel surfaces adapted to engage and grip a flat stud and hold the tie in fixed position, the bent portion of said clip being arranged in close proximity to the front surface of the tie, to 15 permit the rear surface of the tie to snugly engage a collar when the tie is worn.

In testimony whereof I affix my signature.

LORTON A. WESTERVELT.
